FOLDING STOOL

Patrick John Russell, Dublin, Eire

Application June 12, 1943, Serial No. 490,651
In Eire August 25, 1942

7 Claims. (CL. 155—149)

This invention relates to folding stools.

One object of the invention is to provide a folding stool which when collapsed forms a compact bundle and when extended for use provides support for a flexible seat. A further object is to provide a folding stool characterised by two pairs of pivotally connected legs connected by pairs of transverse pivoted struts, with seat supporting cross rails of angle section, pivotally attached at their one ends to the upper ends of one pair of legs whilst their other ends are provided with means for the removable engagement of the rail ends with the tops of the other pairs of legs whereby, in the extended position of the legs and cross rails, a rigid seat supporting structure is obtained whilst, in the collapsed position of the legs and cross rails the latter lie snugly alongside and embrace the detached pair of legs so that the flexible seat can be rolled around the rails and legs and secured by press studs or equivalent fasteners to form a convenient and compact bundle. The cross rails, in their extended position, lie directly over the pivoted struts to effectively brace same and relieve them from strain.

The invention will now be described, by way of example, with reference to the embodiments shown in the annexed drawings wherein—

Fig. 1 is an elevation looking towards the side of one of the pairs of pivoted legs and showing the stool extended for use.

Fig. 2 is a plan view of Fig. 1 with the seat material removed to show the supporting structure more clearly.

Fig. 2^a is an enlarged detail view of the top of the leg with the extension block to which the seat rail is pivotally attached. This view corresponds with the top left hand corner of Fig. 2.

Fig. 2^b is an enlarged detail view of the top right hand corner of Fig. 2.

Fig. 3 is an elevation of the stool corresponding to Fig. 1 and showing the legs and seat rails in their collapsed position.

Fig. 3^a is an enlarged detail view showing the spud and socket for locking the rail ends to the leg tops.

Fig. 4 is an elevation looking in the direction of the arrow X, Fig. 1, and showing the stool extended ready for use.

Fig. 5 is an elevation looking in the direction of the arrow X, Fig. 1, and showing the stool collapsed, the canvas seat 1 being shown in dotted lines so that the legs and seat rails may be shown more clearly.

Fig. 5^a is an enlarged inverted plan view of 55

Fig. 5, looking in the direction of the arrow Y but with the seat material folded to one side for convenience of drawing.

Figs. 6 and 7 are enlarged detail views of a modified support for the seat rails in which metal brackets for the pivots replace the wooden pivot carrying blocks at the top of the legs.

Referring to the drawings:

In the example shown at Figs. 1 to 5 the supporting structure for the flexible seat 1 of a folding stool comprises two pairs of pivotally connected legs 2 and 2^a connected by two pairs of cross struts 3 pivoted at 3^a and having pivotal connection with the legs 2 and 2^a at 3^b. The legs 2 and 2^a are of scissors-like form or formed in a manner similar to a pair of pliers with side to side portions pivotally connected by pivots 4 and terminating at each end in abutting sideward extensions which are each half the width and twice the thickness of the intermediate portions so that in either the extended position of the legs as shown at Fig. 1, or in the closed position of the legs as shown at Fig. 5, the outer surfaces on both sides are flush or in the same plane thereby providing for the convenient attachment thereto of the cross struts 3. For the convenient pivotal attachment to the legs 2^a at one side of the stool of the seat supporting cross rails 5, extension blocks 5^a (see Fig. 4) are provided on the inner sides of the extensions at the top of the legs 2^a and the rail ends are connected thereto by pivots 5^b located as shown so that thereby the rails 5 can, as shown at Fig. 5, lie close along the outer sides of the legs 2 when the latter are in closed-up position. In the example shown the rails 5 are of inverted L-angle section and the side or vertical web of each rail, in the closed position, extends over the side of the adjacent leg 2, keeping the collapsed legs close together while the horizontal or top web lies alongside the outer faces of the legs 2. The ends 5^a of the cross rails 5 are, in the extended position of the legs, engaged with the tops of the corresponding legs 2 (see detail Fig. 3^a) by providing at each of the said rail ends a hole 6 into which a projection or spud 7, provided on the top of each of the legs 2, is adapted to be inserted and so effect locking engagement of the rail ends 5^a with the tops of the legs 2. This arrangement ensures that the seat supporting structure will be held in extended position for effective support and when it is desired to collapse the stool a pull on the legs 2 and/or lifting of the rail ends 5^a will disengage the pins 7 from the holes 6 and the structure can then be folded to the completely collapsed position with the webs

of the cross rails 5 lying along the sides and outer faces of the legs 2 as shown in Fig. 5. Metal brackets 8, as shown in the detail view at Figs. 6 and 7 may replace the blocks 5^c. These brackets are designed to carry the pivots 5^b sufficiently beyond the outer sides of the legs 2^a as to ensure that the horizontal or top webs of the rails 5 will, in the collapsed position, lie close along the outer sides of the detached folded legs 2. The seat rails 5 of angle section have considerable strength, give guiding support to the tops of the legs 2 as they are moved from closed to extended position and they also add to the compactness of the whole structure when closed. In the closed position the flexible seat 1 can be wrapped round the closed rails and legs and secured by means of press stud fasteners 9 on the rails and seat. The article can then be carried like an umbrella. A carrying cord 10 may be provided. A projection 11 may be provided on one or both rails 5 to assist movement of the legs 2 to extended position, said projection being located so as to lie between the legs 2 and 2^a when in closed position and as the rails are moved upwards the projection 11 forces the free legs 2 away from the legs 2^a so that they can then be more easily extended. In the example shown in Fig. 1, the seat 1 is secured to the seat rails 5 by being nailed or glued thereto. When a metal rail is provided, the seat material 1 may be secured by a turned over metal lip 12 as shown at Fig. 6.

What I claim:

1. A stool comprising two pairs of X-formation legs each with a pivotal connection at the intersection so that they can be extended to X-position or in-use position and each having an intermediate part containing said connection and end parts of greater thickness than the intermediate part extending in the direction of the axis of said connection but of lesser width at right angles to said direction than the intermediate parts so that the legs can be collapsed to parallel or out-of-use position forming a composite solid with flush sides, two pairs of X-formation struts in planes transverse to the planes containing the legs and pivotally connected thereto, said struts being extensible to X-formation to space apart the pairs of legs or collapsible to flat position in which they lie between and alongside the legs when the latter are collapsed to parallel or out-of-use position, two transverse rail members of inverted L-cross section having their vertical webs pivoted at or near the tops of the legs of one pair, detachable connection means on said members to engage the top of the other pair of legs when the legs and struts are in extended X-formation to form a rigid structure and a flexible seat-forming means extending between said members, the pivots of said members being so located with reference to the said one pair of legs that when the legs and struts are in collapsed position the transverse members lie alongside the other pair of legs, the vertical and horizontal webs of said members respectively lying alongside the sides and outer faces of the pair of legs other than those to which the rail members are pivotally connected.

2. A stool as claimed in claim 1, in which the detachable connection means between the transverse rail members and a pair of legs comprises stud and socket means.

3. A folding stool comprising two pairs of legs of which each pair consists of two legs having a pivotal connection intermediate their lengths allowing the legs to be moved in planes to an X-

formation in-use position and to a parallel or alongside out-of-use position, two pairs of struts lying in planes transverse to said first planes and each pair comprising two struts each pivotally connected at its ends to legs of the said two pairs of legs and having a pivotal connection intermediate their lengths so that they can be moved to an X-formation position to space apart the pairs of legs or to a collapsed or alongside position in which they lie alongside the legs when the latter are likewise collapsed, a transverse rail member pivotally connected at one end at or near the upper end of each leg of a pair, flexible seat-forming means extending between said transverse members and means for detachably connecting the other end of each member at or near the upper end of the corresponding leg of the other pair when the legs and struts are in extended position to form a rigid structure, the pivotal connection and detachable connection means for said members allowing them to be folded alongside the legs and struts when both the latter are in the collapsed position and the transverse members being of angle section to embrace the detached pair of legs in the collapsed position.

4. A folding stool comprising two pairs of legs of which each pair consists of two legs having a pivotal connection intermediate their lengths allowing the legs to be moved in planes to an X-formation in-use position and to a parallel or alongside out-of-use position, two pairs of struts lying in planes transverse to said first planes and each pair comprising two struts each pivotally connected at its ends to legs of the said two pairs of legs and having a pivotal connection intermediate their lengths so that they can be moved to an X-formation position to space apart the pair of legs or to a collapsed or alongside position in which they lie alongside the legs when the latter are likewise collapsed, a transverse rail member pivotally connected at one end at or near the upper end of each leg of a pair, flexible seat-forming means extending between said transverse members and means for detachably connecting the other end of each member at or near the upper end of the corresponding leg of the other pair when the legs and struts are in extended position to form a rigid structure, the pivotal connection and detachable connection means for said members allowing them to be folded alongside the legs and struts when both the latter are in the collapsed position and each leg comprising an intermediate part of reduced thickness in the direction of the axis of its pivotal connection with the other and the ends of the legs being of reduced thickness at right angles to said direction so that in the collapsed position each pair of legs forms a composite solid with flush sides.

5. A folding stool comprising two pairs of legs of which each pair consists of two legs having a pivotal connection intermediate their lengths allowing the legs to be moved in planes to an X-formation in-use position and to a parallel or alongside out-of-use position, two pairs of struts lying in planes transverse to said first planes and each pair comprising two struts each pivotally connected at its ends to legs of the said two pairs of legs and having a pivotal connection intermediate their lengths so that they can be moved to an X-formation position to space apart the pair of legs or to a collapsed or alongside position in which they lie alongside the legs when the latter are likewise collapsed, a transverse rail member pivotally connected at one end at or near the upper end of each leg of a pair, flexible seat-

forming means extending between said transverse members and means for detachably connecting the other end of each member at or near the upper end of the corresponding leg of the other pair when the legs and struts are in extended position to form a rigid structure, the pivotal connection and detachable connection means for said members allowing them to be folded alongside the legs and struts when both the latter are in the collapsed position and the rail members being of L-cross section and the pivotal connections for said members being spaced out from the pair of legs in the direction of the other pair of legs so that in the collapsed position the members lie parallel with and embrace the other pair of legs.

6. A folding stool comprising two pairs of legs of which each pair consists of two legs having a pivotal connection intermediate their lengths allowing the legs to be moved in planes to an X-formation in-use position and to a parallel or alongside out-of-use position, two pairs of struts lying in planes transverse to said first planes and each pair comprising two struts each pivotally connected at its ends to legs of the said two pairs of legs and having a pivotal connection intermediate their lengths so that they can be moved to an X-formation position to space apart the pairs of legs or to a collapsed or alongside position in which they lie alongside the legs when the latter are likewise collapsed, a transverse rail member pivotally connected at one end at or near the upper end of each leg of a pair, flexible seat-forming means extending between said transverse members and means for detachably connecting the other end of each member at or near the upper end of the corresponding leg of the other pair when the legs and struts are in extended position to form a rigid structure, the pivotal connection and detachable connection means for said members allowing them to be folded alongside the legs and struts when both the latter are in the collapsed position and the members being inverted L-cross section rails with one web of the cross section horizontal in the in-use position, said webs being so spaced from the correspond-

ing pivotal connections with the pair of legs that in the collapsed position they embrace and lie parallel to the outer faces of the other pair of legs and in conjunction with the other webs provide guiding support to said other pair of legs as the struts are moved from collapsed to extended position.

7. A folding stool comprising two pairs of legs of which each pair consists of two legs having a pivotal connection intermediate their lengths allowing the legs to be moved in planes to an X-formation in-use position and to a parallel or alongside out-of-use position, two pairs of struts lying in planes transverse to said first planes and each pair comprising two struts each pivotally connected at its ends to legs of the said two pairs of legs and having a pivotal connection intermediate their lengths so that they can be moved to an X-formation position to space apart the pairs of legs or to a collapsed or alongside position in which they lie alongside the legs when the latter are likewise collapsed, a transverse rail member pivotally connected at one end at or near the upper end of each leg of a pair, flexible seat-forming means extending between said transverse members and means for detachably connecting the other end of each member at or near the upper end of the corresponding leg of the other pair when the legs and struts are in extended position to form a rigid structure, the pivotal connection and detachable connection means for said members allowing them to be folded alongside the legs and struts when both the latter are in the collapsed position and said members being rails of inverted L-cross section having side and top webs and pivotally connected by their side webs to one pair of legs and the side webs and top webs being adapted respectively to engage the sides and outer faces of the other pair of legs in the collapsed position, the side webs having projection means adapted to be located between the opposed inner faces of the pairs of legs in said collapsed position which projections serve to force apart the pairs of legs when said members are moved to the extended or in-use position.

PATRICK JOHN RUSSELL.
